UNITED STATES PATENT OFFICE.

FRANK A. GUSTAVSON, OF SEEKONK, MASSACHUSETTS.

VENTILATOR AND AIR-PURIFYING APPARATUS.

1,270,613.

Specification of Letters Patent. Patented June 25, 1918.

Application filed May 31, 1917. Serial No. 171,858.

To all whom it may concern:

Be it known that I, FRANK A. GUSTAVSON, a subject of the King of Sweden, and resident of Seekonk, in the county of Bristol and State of Massachusetts, have invented certain new and useful Improvements in Ventilator and Air-Purifying Apparatus, of which the following is a specification.

This invention relates to ventilating and air-purifying apparatus, which may be applied to a window or other opening in the wall of a building, and the object of this invention is to provide such an apparatus with an oscillating flue casing having a mechanically driven fan mounted therein for forcing fresh air into the room.

A further object of the invention is to provide a reservoir in the casing filled with a deodorizing or germicide agent.

20 A still further object of the invention is to provide means whereby air may be driven into the casing by the fan from two or more different sources, to be acted upon by the deodorizing agent before being expelled 25 from the casing into the room.

A still further object of the invention is the provision of a roll of filter screen cloth having a section covering the discharge end of the casing, whereby a fresh section may 30 be drawn from the roll over the casing end as often as desired.

With these and other objects in view, the invention consists of certain novel features of construction, as will be more fully described, and particularly pointed out in the appended claim.

In the accompanying drawings:

Figure 1— is a side elevation partly in section showing the operating mechanism 40 of my improved ventilating apparatus.

Fig. 2— is a plan view of the ventilating apparatus also partly in section.

Fig. 3— is a section on line 3—3 of Fig. 2 showing the preferred form of the casing 45 in cross section.

Fig. 4— is a detail plan view showing the means for withdrawing the oscillating actuating mechanism from operative position.

Referring to the drawings, 10 designates 50 the flue casing which is herein shown as being substantially square in cross section, but which may be made in any desired form. The outer end 11 of this casing is preferably rounded on a radius struck from the center 12 on which the casing rotates, and

this rounded end extends into the opening 13 in the wall 52 of the building.

A roll 14 is mounted on suitable bearings on the top and at the inner end of this casing 10, on which roll is wound a length of 60 screen cloth 15, which may be of any suitable material, but is preferably formed of cloth which is sufficiently permeable to take up moisture, retain the germs and prevent the impurities from entering the room there- 65 through, said screen forming the inner end wall of the casing.

By mounting a long length of this cloth on the roll a fresh portion may be readily drawn from the roll over the casing-end as 70 often as desired. This cloth is led back of the cutter plate 16 against the lower edge of which the used portion 17 of the cloth may be torn when a fresh section is drawn thereunder. The edge of this cloth is secured to 75 the curved lip 18 about the casing-end by means of a spring wire clip 19 and the whole is supported on a frame 20 hinged at the top at 21 and is secured at its lower edge 22 by the spring latch 23, whereby the whole 80 end of the casing may be swung up when desired, to inspect the interior thereof.

On the inner side of this casing is mounted a rotatable fan 24 on the hub 25, which fan is driven through the miter gears 26, 85 upright shaft 27, miter gears 28, horizontal shaft 29 and motor 30, but any other suitable means may be employed for driving the shaft 29.

This whole casing is mounted to oscillate 90 on a trunnion 31 set in the supporting frame 32 on ball bearings 33, the oscillating motion being imparted by means of the crank disk 34 through the connecting rod 35, which rod is attached at one end 36 to 95 the casing and at its opposite end to this disk 34, the latter being driven from the shaft 29 through the worm 38, worm-gear 39 and short upright shaft 40, whereby as the shaft 29 rotates to drive the fan, motion 100 is also imparted through the mechanism above described to slowly oscillate the casing and so better distribute and diffuse the incoming air in the room.

In some cases it is found advisable to provide a receptacle 41 for a deodorizing or disinfecting agent, such as carbolic acid or other suitable germicide, and to provide a deflecting plate 42 for conducting the air over the surface of this liquid. It is also 110

found of advantage to provide a curved partition 43 which provides a mixing chamber at the rear of the casing and also deflects the air downward over the germicide 6 receptacle.

By this construction the inflowing air is first directed over the surface of the germicide and then upward by coming in contact with the end wall screen thereby causing a 10 more thorough mixing in this chamber, with the fumes of the germicide from the reservoir. After this mixing action the air passes through the screen and out into the room.

15 Across the front opening 13 in the wall 14, I have provided a screen 44 which prevents foreign matter from entering from the outside air, and the quantity of this air may be nicely regulated by means of the 20 closure or swinging door 45, which is hinged at its upper edge 46, and is provided at its lower edge with a regulating bar 47 which extends through the wall to the inside of the room.

25 A rain guard 48 is formed over the hinge 46 to prevent moisture from entering through the swing joint.

A feature of this invention is that air 30 may be drawn into the casing from a plurality of sources, that is, some fresh air may be drawn in from out of doors and some of the air from the room may be also drawn into the casing and from either or both sides of the casing and after having 35 been treated with germicide, is forced out into the room.

To accomplish this, I have provided screens 49 supported on spring rolls 50 and led over guide rolls 51, thence close 40 around the face of the circular end of the casing and secured at 52 on the sides thereof.

The casing which is mounted to oscillate on its trunnion 31 is adapted to swing about 45° each side of the center line of the opening; therefore its open end which corresponds in width to the opening 13 in the wall, upon being swung first to one side and then to the other presents an open space to the inside of the room on alternate sides 50 and as the front end of the casing swings to the right the screen 49 on that side is

drawn out from its roll and covers the opening presented to the room to screen the incoming air, and the corresponding screen on the opposite side is wound upon its roll 55 and so as the casing oscillates first one and then the other of these screens is called upon to close the opening as formed and so prevent foreign matter from being drawn into the casing from the room. 60

It is found in some instances desirable to run the fan without providing an oscillating motion to the casing, and to accomplish this, I have provided a bearing block 53 for the crank disk shaft 40 and this block 65 is mounted in a frame 54 so that the whole may be slid sidewise in this frame by means of the pin 55 to withdraw the gear 39 from the worm 38 and so prevent further oscillation of the casing until this gear has been 70 pushed back into operative position.

My improved apparatus may be used either as an oscillating or as a stationary air purifier, deodorizer, humidifier or fumigator and is designed to be operated not 75 only as a wall or window ventilator but may be used as well in centers or placed about large department stores, theaters, halls, schools, churches or other buildings where a large number of people assemble. 80

The foregoing description is directed solely toward the construction illustrated, but I desire it to be understood that I reserve the privilege of resorting to all the mechanical changes to which the device is 85 susceptible, the invention being defined and limited only by the terms of the appended claim.

I claim:

An air-purifying and ventilating apparatus comprising a casing, means in said casing for carrying a deodorizing agent, means for drawing air into said casing from a plurality of different sources at successive intervals of time, forcing the air into contact with the deodorizing agent and out of the casing. 90

In testimony whereof I affix my signature in presence of a witness.

FRANK A. GUSTAVSON.
